S. L. BENNETT,
SPEED INDICATOR.
APPLICATION FILED OCT. 6, 1917.

1,266,763.

Patented May 21, 1918.

UNITED STATES PATENT OFFICE.

SAMUEL LESLIE BENNETT, OF BELLOWS FALLS, VERMONT, ASSIGNOR TO THE VERMONT FARM MACHINE COMPANY, OF BELLOWS FALLS, VERMONT, A CORPORATION OF VERMONT.

SPEED-INDICATOR.

1,266,763.

Specification of Letters Patent.

Patented May 21, 1918.

Application filed October 6, 1917. Serial No. 195,068.

To all whom it may concern:

Be it known that I, SAMUEL LESLIE BENNETT, a citizen of the United States, residing at Bellows Falls, in the county of Windham and State of Vermont, have invented 5 a certain new and useful Improvement in Speed-Indicators, of which the following is a full, clear, and exact description.

The object of this invention is to provide 10 a rotary machine with an audible signal or indicator, which will aid the operator in running the machine at the desired speed, by sounding when the speed is less than the desired speed or the speed necessary to obtain 15 the greatest efficiency in the operation of the machine.

Without thereby limiting the invention, I have herein shown the same applied to a 20 centrifugal cream separator mechanism, adapted to be operated by hand, and in which a bell is used as the audible signal or indicator, which is rung or sounded only when the speed falls below the desired speed for most efficiently separating cream.

25 Cream separators may be geared for most effective work to any desired speed, within given limits, and hence the mechanism of the present invention will be so designed and arranged as to sound the alarm whenever 30 the speed is below whatever is the predetermined or normal speed, and to cease sounding when the normal speed is reached or exceeded; a speed in excess of normal if not too great being negligible and quite obvious 35 to any one familiar with the operation of the machine and watching its product.

The invention consists of an arm pivoted 40 to a member of the gearing and subject to centrifugal action, and a bell or other audible signal interposed in the path or arc of movement of the arm in such way that the arm when carried at a speed below normal will sound the bell and thus indicate to the operator that a normal speed is not attained; 45 and by centrifugal action will fly out of the path of contact with the bell-actuating means and thus permit the bell to remain silent for the time being or as long as the normal speed or a speed more or less in excess thereof is 50 continued, as I will proceed now to explain and finally claim.

In the accompanying drawings illustrating 55 the invention, in the several figures of which like parts are similarly designated, Figure 1 is an elevation showing the crank

and crank shaft, a portion of a centrifugal cream separator bowl and its spindle, and interposed gearing, with the speed indicator in position, the bell-actuating arm being out of contact with the bell. Fig. 2 is a similar 60 elevation of the signaling mechanism alone with the bell-actuating arm in position to sound the alarm. Fig. 3 is a perspective view of the bell-actuating arm detached. Fig. 4 is a perspective view of the bell hammer and its lever detached.

1 is a hand crank mounted on shaft 2, to turn the same, and 3 is a gear wheel on said shaft meshing with a gear wheel 4 on the shaft 5 on which is an intermediate gear 70 wheel 6 which meshes with a gear wheel 7 on a shaft 8 on which is a worm wheel 9 meshing with a worm 10 on the spindle 11 of the separator bowl 12. This mechanism is a well-known mechanism, and its operation 75 needs no further description here. It is sufficient to say that the train of gears is so proportioned as to give the desired speed to the separator bowl at a given number of revolutions of the shaft 2, and that being determined, the mechanism for sounding the 80 alarm is arranged to become effective in a way to indicate the loss of speed or lack of speed.

In the embodiment of the invention herein 85 shown, an arm 13 is eccentrically pivoted at 14 to the web of the gear wheel 6, and its outer free end extends toward the periphery of the gear wheel, and may be counterweighted if desired. This arm is provided 90 with a pin 15 standing off therefrom at right angles; and this end of the arm has a limited motion between two pins or stops 16 and 16' fastened in the web of the gear wheel 6 at such distances from the axis of shaft 5 as 95 to arrest the movement of the arm upon the rotating gear wheel. The points of contact between the arm 13 and the pins 16 and 16' may be deadened by any suitable means, such as the cushion or cushions 17 carried 100 by the arm. The arm 13 freely plays by gravity between the pins 16 and 16' when the speed is less than the desired speed, and in going from pin 16 to pin 16' as indicated by dotted lines Fig. 1, it presents its pin 105 15 in the path of a pin 18 on the bell crank or lever 19 which carries the bell hammer 20 of the bell 21. The bell may be mounted on any suitable portion of the frame of the machine, preferably on the outside. When 110

the pin 15 strikes the pin 18 the bell hammer is actuated to sound the bell, and the bell will be sounded as long as the pin 15 comes into contact with its actuating lever, 5 but as soon as the normal speed is attained then centrifugal action will hold the arm 13 against the stop pin 16 and thus prevent its pin 15 from coming into the path of the pin 18 and actuating the bell.

10 As already stated, so long as the bell rings it will be notice to the operator that normal speed has not been attained, and consequently the operator will increase the speed by more rapidly turning the crank 1, until 15 the bell no longer rings, and he will thereafter maintain the speed at that rate, although no material harm will follow from a speed in excess of normal speed within reasonable limits easily observable by the operator or any one familiar with the desired product of the machine.

20 As shown in Fig. 1, the hammer or clapper mechanism is held in proper position to be engaged by the centrifugally operated arm 25 by means of a spring 22, although of course any equivalent mechanism may be used for this purpose.

25 In the case of centrifugal cream separators turned by hand, a certain number of revolutions of the crank are necessary to give the bowl exactly the right number of revolutions to obtain an efficient and economical separation of the fluid under treatment, and in 30 order to obtain this desired speed, the operator turns the crank, and while the bell sounds there is indicated a speed below normal, and he therefore continues to increase the number of turns of the crank until the bell ceases sounding, and then he knows that 35 40 the desired speed has been attained. As already stated, a little higher speed does no harm, while a speed lower than that desired is at once made known by the ringing of the bell.

45 Variations in details of construction and arrangement to suit the character of machine on which the indicator is used, are permissible within the principle of the invention and the scope of the claims herein made.

50 What I claim is:—

1. A speed indicator, comprising a rotat-

ing member, a centrifugal arm eccentrically pivoted on said member, and an audible alarm having its actuating mechanism extending into the path of movement of the 55 centrifugal arm and adapted to be acted upon by said arm when the speed of the rotating member is below normal so as to sound the alarm and to be free of such action when the speed attained is at or above 60 normal.

2. A speed indicator, comprising a rotating member, a centrifugal arm pivotally mounted on said member and having a gravitating motion between stops on said member, 65 and an audible alarm having its sounding mechanism interposed in the path of movement of the centrifugal arm and adapted to be acted upon by said arm when the speed of the rotating member is below normal 70 and to be free of such action when the speed attained is at or above normal.

3. A speed indicator, comprising a rotating member, a centrifugal arm pivotally mounted on said member, stops on said member to limit the pivotal movement of said arm, and an audible alarm having its sounding mechanism interposed in the path of movement of the centrifugal arm and adapted to be acted upon by said arm when the speed of the rotating member is below normal 75 and to be free of such action when the speed attained is at or above normal.

4. A speed indicator, comprising a rotary member, an arm pivotally mounted on said 85 member and having a restricted path of movement thereon, and an audible alarm provided with a lever projecting into the path of movement of said pivoted arm and adapted to be engaged by said arm when the rotation of the rotary member is less than 90 normal and to be free of engagement therewith when the speed of the rotary member is at or above normal.

In testimony whereof I have hereunto set 95 my hand this fourth day of October, A. D. 1917.

SAMUEL LESLIE BENNETT.
